UNITED STATES PATENT OFFICE

MARSHALL R. MYERS, OF AFTON, IOWA

AIRSHIP CONSTRUCTION

Application filed February 25, 1928. Serial No. 257,003.

My invention relates to improvements in airship constructions, and it consists in the combinations, constructions, and arrangements herein described and claimed.

An object of my invention is to provide an airship construction which has novel means whereby the airship will automatically right itself without the aid of the motor power.

A further object of my invention is to provide a device of the type described wherein the wings are disposed in somewhat of a compact form adjacent the propellers—thus obviating the additional weight created by the outspreading wings of the ordinary aero-plane.

A further object of my invention is to provide a device of the type described in which the wing construction aids in lifting the airship.

Other objects and advantages will appear in the following specification, and the novel features of the invention will be particularly pointed out in the appended claims.

My invention is illustrated in the accompanying drawings, forming part of this application, in which

Figure 1 is a top plan view of my device,

Figure 2 is a section substantially along the line 2—2 of Figure 1, and

Figure 3 is a section substantially along the line 3—3 of Figure 1.

In carrying out my invention, I provide a frame 1 having a front portion 2, a rear portion 3, and side portions 4 and 5 which taper inwardly from the front portion 2 to the rear portion 3. I provide a cabin 6 which is mounted upon the frame at substantially the center thereof and which extends from the front portion 2 to substantially adjacent the rear portion 3 of the frame.

Relatively large front wings 7 and 8 are mounted upon the frame 1 by means of relatively long supports 9. The wings 7 and 8 are semi-circular in cross section and the walls thereof taper from relatively large inlets 10 to relatively small outlets 11. Relatively small rear wings 12 and 13 are mounted upon the frame 1 by means of supports 14. The wings 12 and 13 are semicircular in cross section and are tapered from relatively large in-

lets 15 to relatively small outlets 16. The front wings 7 and 8 are distinguished from the rear wings 12 and 13 by stating that the front wings are relatively large and the rear wings are relatively small. However, it is 55 obvious that there is not an extreme difference between the sizes of the two sets of wings. The same is true with the inlets and outlets of the two sets of wings in that there is not a great difference between the size of the inlets and the size of the outlets. However, the difference is sufficiently great for the purpose intended, which will hereinafter be described.

Motors 17 and 18 are mounted upon the frame 1 beneath the front wings 7 and 8 and are operatively connected to propellers 19 and 20 by means of shafts 21 and 22, respectively.

Banking rudders or ailerons 23 and 24 are hingedly connected to the frame 1 at the rear of the front wings 7 and 8. The banking rudders 23 and 24 are operated from the cabin 6 by any suitable means not shown. Rear rudders 25 and 26 are hingedly connected to the frame 1 at the rear portion thereof and are operated from the cabin 6 by any suitable mechanism, not shown. Front carriers 27 and rear carriers 28 are secured to the frame 1 and extend therebeneath.

From the foregoing description of the various parts of the device, the operation thereof may be readily understood. Let us assume that the motors 17 and 18 and the propellers 19 and 20 are in motion. The motion of the propellers tends to draw the airship forwardly. When the airship is traveling at a desired speed, the rear rudders 25 and 26 may be swung upwardly—thus causing the airship to rise. When the airship has reached the desired height, the rear rudders may be again lowered until they are in the general plane of the frame 1.

The front wings 7 and 8 are of a sufficient size so as not to be disturbed by the motion of the air which is created by the propellers. However, the rear wings are smaller in size 95 and are of a sufficient size to be affected by the air created by the movement of the propellers. The air created by the propellers in passing through the rear wings provides sufficient force for supporting the rear end of the 100

airship. The pilot may turn the airship in any desired direction by lowering one of the banking rudders and raising the other banking rudder; as, for instance, let us assume that the pilot is desirous of turning the airship to the right. By lowering the banking rudder 23, the left side of the airship will be raised and, by raising the banking rudder 24, the right side of the ship will be lowered and in this manner the ship will travel through an arcuate-shaped path to the right. The airship may be turned to the left in the same manner, only by raising the banking rudder 23 and lowering the banking rudder 24.

15 It is obvious that the cabin 6 is disposed at the center of the airship between the front wings and between the rear wings. It is also obvious that the cabin is disposed between the motors. Therefore, if the airship is used 20 in time of war, the occupants of the cabin may have free range either forwardly or rearwardly without the need of shooting through the propellers.

Furthermore, due to the fact that the wings 25 are positioned substantially adjacent the motors and the propellers, one motor may stop completely and the airship may be caused to travel in safety by the operation of only one motor and propeller. Let us assume that the 30 motor 17 ceases to operate. The pilot may readily observe when there is trouble with the motor and may shut off the motor entirely. However, to balance the ship, the banking rudder 23 is swung downwardly so as to tend 35 to lift the left side of the airship. The mechanician may then step from the cabin 6 and place the motor in its proper operative position again.

I claim:

40 1. A device of the type described comprising a frame, a front wing mounted upon said frame and arcuate-shaped in cross section, a rear wing mounted upon said frame and arcuate-shaped in cross section, a propeller disposed in front of said front wing, means for actuating said propeller for moving said frame and said wings forwardly, the rotation of said propeller forcing air rearwardly through said front wing and said rear wing, 45 said rear wing being relatively small and having tapered walls whereby the air from said propeller will engage with said walls for supporting the rear portion of said frame and said rear wing, guide means disposed between 50 said wings, and elevating means disposed at the rear of said rear wing.

55 2. A device of the type described comprising a frame, a pair of front wings arcuate-shaped in cross section disposed upon said frame, a propeller disposed in front of each of said front wings, means for rotating said propellers, a cabin disposed between said front wings, a pair of relatively small rear wings disposed at the rear and in substantial 60 alignment with said front wings, said rear

wings being arcuate-shaped in cross section and having tapered walls, the rotation of said propellers forcing air through said front wings and said rear wings, the air in passing through said rear wings engaging with the tapered walls thereof for supporting said rear wings, guide means disposed between said front wings and said rear wings, and elevating means disposed at the rear of said rear wings.

Signed at Afton, in the county of Union and State of Iowa this 18th day of February A. D. 1928.
